UNITED STATES PATENT OFFICE

JOHN GELOSO, OF NEW YORK, N. Y., ASSIGNOR, BY MESNE ASSIGNMENTS, TO PILOT RADIO & TUBE CORPORATION, OF BROOKLYN, NEW YORK, A CORPORATION OF DELAWARE

INDICATOR ELEMENT

Application filed March 21, 1928. Serial No. 263,386.

This invention relates to improvements in control elements for radio receiving apparatus, being particularly directed to indicating mechanism applied in association with said 5 control elements.

Broadly it is an object of this invention to provide for a novel form of control for operating the tuning means or other electrical elements of a radio receiver, from the front 10 panel of the receiver, the degree of displacement or actuation of said tuning means or other electrical elements being illustrated at the front of the panel by means of illuminated visible indicators adapted to be progressively 15 disclosed.

Specifically this invention contemplates the application of mechanism actuated at the front of the panel for controlling the movement of tuning or other electrical members 20 disposed to the rear of the panel, through intermediate means operable directly from controls on the front panel and which intermediate means carries indicia thereon whereby the degree of displacement of the tuning or other 25 electrical means is visibly and clearly disclosed to the operator at the front of the panel.

Further it is an object of this invention to provide for a control for the tuning elements 30 or other electrical elements in a radio receiver, comprising of a drum member coupled and rotatable with the tuning or other elements and operable from the front panel of the receiver through actuation of a knob or control 35 means, the said drum being adapted to have indica thereon, which are disclosed to the operator through the illuminated aperture at the front of the receiver.

Still further it is an object of this invention 40 to provide for a control for tuning or other electrical elements in a radio receiver comprising of a drum or series of drums coupled with said tuning or other units, all of which 45 are disposed to the rear of the panel and which tuning or other electrical units are actuated through the displacement of said drum or drums carrying indica thereon, through the medium of a friction drive act- 50 ing upon the drum or drums and controllable

through the operation of a knob at the front of the panel.

In general then it is an object of this invention to provide for a control for tuning or other electrical units, comprising drum members 55 coupled therewith, which drum members have indicia thereon capable of being visible to the operator at illuminated apertures in the front panel whereby to indicate the degree of displacement of said electrical units; the said drum elements being actuated through the friction drive operable from the front panel 60 of the radio receiver.

These and other advantages, capabilities 65 and features of the invention will appear from the subjoined detail description of one specific embodiment of the invention illustrated in the accompanying drawings, in which

Figure 1 represents a front view of the 70 device.

Figure 2 represents a plan view of the device.

Figure 3 represents a side elevation partly 75 in section of the device.

Figure 4 represents a plan view partly in section of the operating mechanism in the device.

Referring to the reference characters in the drawing numeral 10 represents the front 80 panel of a radio receiver upon which there is mounted an escutcheon plate 11 having therein the offset projection 12 which is disposed into the aperture formed in the panel and in which offset portion of said escutcheon 85 plate there are adapted to be stamped or cut out portions 13 and 14, to respectively allow for the disclosure of the indicating means on the dial to be later described, and the passage of light from the illuminating means to be 90 later described upon the indicating means disclosed in the aperture 13 whereby the operator may have a visible illuminated record of the changes in the conditions within the receiver.

To the rear of the panel 10 there are disposed the electrical elements to be controlled and which in this instance are indicated as tuning units or condensers 15 which are coupled to drum elements 16 whereby rota- 95 100

tion of the drum about its shaft 17 will cause the rotation, of the condensers since the condenser shaft is an integral extension of the drive shaft or vice versa, the lock nut 18 on the bearing member 19 positioned in the condenser frame, being adapted to provide for a means, serving in conjunction with the pillar 20 to provide a two point support for the condenser 15 on the frame 21.

10 The shaft 17 as shown in Figure 4 is adapted to fit in the hub 22 of the drum 16 being screw threaded as at 23 at one extremity thereof for being locked for rotation with the drum by means of the nut 24. An enlarged shoulder 25 is formed integrally with the shaft 17, the shoulder extending only for a portion of the length of the shaft but having one extremity thereof forming a flush contact, with the face or surface of the hub 22 20 of the drum 16 and being adapted to rotate within the journal or bearing 26 comprising a sleeve formed integral with the support bracket 21, which extends to a point adjacent but not touching the surface of the hub 22.

25 The shaft 17 is locked for lateral displacement, adjacent the face of the support bracket 21 by means of a lock nut 27 having a set screw 28 therein, the shaft being adapted to extend through the end plates of the condenser, and carrying the rotor plates thereon through means well known in the art preferably through either a casting carrying the plates and fixed to the shaft or a series of washers between the plates and the whole 35 of which are locked for rotation with the shaft.

The drum member 16 comprises a casting formed of a phenolic condensation product, hollow in its interior, and having a wall in 40 the form of a circular projection formed integral with the outer face or base thereof, this wall 29 being integrally formed with the base adapted to be annular and adjacent the outer periphery of the drum and serving to 45 be contacted by driving means to be later described. The circumferential or body formed portion 30 of the drum 16 has either pasted or fixed thereto in any manner an indicator strip 31, which indicator strip has indicia 50 thereon, which indicia are visible through the apertures 13 in the escutcheon plate 11, as shown in Figure 1.

The driving means for the actuation of the drum comprises a plurality of friction disks 55 32 and 33 formed on the drive shaft 34, mounted in bearing 35, which is locked to the front panel by the nut and washer formation 36, and passes through the arm 37 of the frame support member 21, which arm is bent right angularly to the body of the frame support and maintained in fixed position, so as to be pressed toward the inner wall of the panel by means of the bushing 39 on one end of the bearing 35 so that the bearing 35 serves to both carry the drive shaft

34, and the support bracket 21 carrying the mechanism actuated by the drive shaft.

The friction disks 32 and 33 are positioned on opposite sides of the projection 29, on the drum, the disk 33 being adapted to abut the surface of the bearing 35 and being fixed to the shaft, the second of said disks 32 being adapted to be positioned on the opposite side of the projection or wall 29 and having a reduced shoulder 40 upon which spring member 41 on the shaft 34 is adapted to rest, said spring member being compressed between nuts 42 threaded to the shaft 34 at its extremity, and the side wall 43 of the friction disk 32 so as to urge the same laterally at all times into contact with the surface of the wall 29; one of the two disks 33 being fixed to the shaft or formed integrally thereof and the other disk 32 being forced by pressure to be frictionally rotatable therewith. The actuation of the shaft 34 through movement of the control knob 38 will cause frictional contact of the disks 32 and 33 with the projection 29 and thus the actuation of the drum and with it the rotor plates of the condenser associated therewith.

Adjacent the projection 12 of the escutcheon plate extending interiorly of said panel 10 there is adapted to be carried on the bracket 44, on electric light 45 having terminals 46 and 47 for interconnecting the same with a source of current, the electric light being positioned directly above the aperture 14 of the projection 12 of the escutcheon plate, so that the indicia on the drum are visible to the observer through the apertures 13 in the escutcheon plate are illuminated by the passage of light rays along the cut out portion 14 and striking the exposed indicia, as in Figure 1, the cut out portion 14 being as shown 100 in Figure 1 in the shape of a chamber through which light may be guided downwardly.

It is obvious that various changes and modifications may be made to the details of construction without departing from the general 110 spirit of the invention set forth in the appended claims.

I claim:

1. In a radio receiver, the combination with a front panel having control means thereon, of a shaft fixed to said control means, and passing through said panel, tuning means to the rear of said panel, a drum carrying indicating means coupled with said tuning means, means on said shaft for rotating the drum, an escutcheon plate on the front of the panel having apertured projections extending rearwardly through an opening in said panel, the first of the apertures in said projections serving to disclose indicia on said drum, and the second of said apertures serving to allow passage of light from illuminating means positioned on the rear of said panel upon the disclosed indicia on the drum whereby to make the same visible to the observer.

2. In a radio receiver, the combination with a front panel having control means thereon, of tuning means to the rear of said panel, a drum member carrying indicia coupled with said tuning means, means operable by said control member for actuating said drum member, an aperture formed in said front panel, whereby to disclose indicia on said drum member and a second aperture in a plane angularly disposed with respect to said first named aperture and means adjacent and to the rear of the second named aperture for illuminating the indicia disclosed in said first named aperture.
3. In a radio receiver, the combination of a front panel, of control means to the front of said panel, a shaft fixed to the control means and passing to the rear of said panel, tuning means to the rear of said panel, a drum member carrying indicating means thereon coupled with said tuning means, and positioned to the rear of said panel, means on said shaft for actuating the drum member, an aperture in said front panel, an escutcheon plate fixed to the front of the panel and having apertured projections extending within the aperture in the panel and rearwardly thereof, some of the apertures of said escutcheon plate being adapted to disclose a portion of the indicating means, illuminating means to the rear of said panel, and the other of said apertures in the escutcheon plate being adapted to direct light from said illuminating means on said disclosed portions of said indicating means.
4. In a radio receiver, the combination with a front panel, having an escutcheon plate thereon, of tuning means to the rear of said panel, indicating means coupled with said tuning means, and disposed rearwardly of said escutcheon plate, control means passing through said panel and escutcheon plate for actuating said indicating means, a plurality of apertures in said escutcheon plate in different formed planes, the apertures in one plane being adapted to disclose indicia on said indicating means, and means adjacent the apertures in the other plane for illuminating the indicating means disclosed through said first named apertures.
5. In a radio receiver, the combination with a front panel, having an escutcheon plate thereon, of a tuning mechanism, to the rear of said panel, indicating means associated with said tuning means, an aperture in said escutcheon plate, for disclosing the indicia on the indicating means, and a second aperture in said escutcheon plate, angularly disposed from the first said aperture, and means adjacent said second aperture for illuminating the indicia on the portion of the indicating means disclosed in said first named aperture.
6. In a radio receiver, the combination with tuning means, and indicating means associated therewith, of a panel member carrying a control through which said indicating and tuning means may be actuated, illuminating means to the rear of said panel, said panel having provided therein, a plurality of apertures, angularly disposed from one another, whereby one of said apertures may disclose the indicia on the indicating means and the other of said apertures may allow the passage of light from the illuminating means in the direction of the disclosed indicia, whereby to provide for clear illuminated visibility.
7. In a radio receiver the combination with a front panel having control means thereon, of tuning means to the rear of said panel, a drum member carrying indicating means on its circumferential periphery, said drum member being coupled with tuning means, a circular flange formed along the base of said drum member, and offset from the outer periphery of said drum member, a shaft extending from said control means through said panel, and friction driving means on the shaft, coacting with said flange, whereby to actuate said drum and said tuning means.
8. In a radio receiver the combination with a front panel, having control means thereon, of tuning means to the rear of said panel, a drum member carrying indicating means on its circumferential periphery, said drum member being coupled with said tuning means, a circular flange formed along the base of said drum member and offset from the outer periphery of said driving member, a shaft extending from said control means through said panel, and friction driving means on the shaft, coacting with said flange, whereby to actuate said drum and said tuning means, and means for maintaining the pressure of said friction driving means, whereby to provide for constant contact of the same against the flange on said drum.
9. In a radio receiver, the combination with a panel, of control means to the front of said panel, a shaft fixed to the control means and passing to the rear of said panel, tuning means to the rear of said panel, a drum member carrying indicating means on its circumferential periphery, said drum being coupled with tuning means and positioned to the rear of said panel, an aperture in said panel through which a portion of said indicating means may be visible, and an annular projection formed on the base of said drum adjacent the circumferential periphery thereof, and means on said shaft for frictionally contacting with said projection, whereby to actuate the drum member and the tuning means.

JOHN GELOSO. 125
